AQUARIUM FILTER HOUSING

Morris R. Gare, Hillside Township, Union County, N.J.
(4 Bruen St., Newark, N.J. 07105)

Filed Feb. 10, 1966, Ser. No. 1,008

Term of patent 14 years

(Cl. D91—1)

FIG. 1

FIG. 3

FIG. 1 is a perspective view of an aquarium filter housing embodying my new design,

FIG. 2 is a top plan view thereof, and

FIG. 3 is an end elevational view thereof.

I claim:

The ornamental design for an aquarium filter housing, as shown.
